UNITED STATES PATENT OFFICE.

GEORGE C. HOHEIN, OF NORFOLK, VIRGINIA.

MIRROR FOR BARBERS' CHAIRS.

No. 806,742.

Specification of Letters Patent.

Patented Dec. 5, 1905.

Application filed February 23, 1905. Serial No. 247,011.

To all whom it may concern:

Be it known that I, GEORGE C. HOHEIN, a citizen of the United States, residing at Norfolk, in the county of Norfolk and State of Virginia, have invented new and useful Improvements in Mirrors for Barbers' Chairs, of which the following is a specification.

My invention relates to mirror attachments for barbers' chairs; and its primary object is 10 to provide a new and useful device of this character adapted to be applied to a barber's chair to cast a reflection of the back of the occupant's head in the mirror usually arranged in front of such chairs.

15 A further object of the invention is to provide a device adapted to adjustably support a mirror whereby the mirror may be retained in or out of operative position and adjusted vertically or horizontally. The device when 20 retained out of operative position occupies such a place upon the back of the chair that all liability of its being in the way is obviated.

25 A still further object of the invention is to provide a device of the above-stated character which is cheap to manufacture, durable and efficient, and constructed of few parts so arranged and constructed as not to be liable to become broken or inoperative.

The invention consists in the construction, 30 combination, and arrangement of parts hereinafter fully described, claimed, and illustrated in the accompanying drawings, which disclose the preferred form of my invention, and in which—

35 Figure 1 is a rear elevation of a barber's chair illustrating the application of my improved mirror-support thereto. Fig. 2 is a detail side elevation of the support, a portion thereof being in longitudinal section and the 40 mirror being illustrated as in operative position. Fig. 3 is a view similar to Fig. 2, the mirror being illustrated in its inoperative position. Fig. 4 is a detail perspective view of the mirror-frame and rod to which the mirror-frame is adjustably secured, and Fig. 5 is 45 a detail perspective view of the bracket which is adapted to secure the mirror-support in applied position.

Referring to the drawings by reference- 50 numerals, 1 designates a barber's chair of the usual construction, and 2 the rear face of the back thereof. The mirror-support is adapted to be secured to the back 2, so as to permit the mirror to be moved upwardly above the 55 upper edge of the back to place the mirror in operative position and moved downwardly

below said upper edge into its inoperative position and out of the way.

3 designates a bracket which is secured to the rear face of the back 2 centrally thereof 60 and at a point adjacent its lower edge, and it comprises a base-plate 4, carrying a vertically-arranged sleeve 5, secured to and spaced from said base-plate by means of a connection 6.

The base-plate is provided with a plurality of 65 openings 7, through which screws or other fastening means pass to engage the back 2 to secure the bracket in applied position, and the sleeve 5 is provided with a screw-threaded opening 8, adapted to receive a thumb-screw 70

9. A hollow member 10 is mounted within the sleeve 5 for vertical adjustment and is adapted to be held in its adjustment by means of the thumb-screw 9. This member is closed at its lower end and open at its upper end for 75 the reception of a supporting-rod 11, which is also adapted for vertical adjustment and which is adapted to be held in its adjusted position by means of a thumbscrew 12, carried by the hollow member 10. The upper end of 80 the supporting-rod 11 is disposed horizontally and provided with a ball adapted to be received by a socket 13, carried on the rear face of a mirror-carrying frame 14, whereby the mirror 15, carried thereby, is adapted for adjust- 85

ment with relation to said rod 11. A thumb-screw 15^a is carried by the socket 13 to bind the socket upon the ball to secure the mirror-frame in its adjusted position. A spring 16 is situated 90 within the hollow member 10 and has its upper end secured to the lower end of the rod 11 and its lower end secured to a hook 17, carried by the lower closed end of said member. This spring is retractile in its nature, and consequently retains said rod drawn downwardly 95

within the hollow member, as disclosed in Fig. 3 of the drawings, whereby the mirror is normally retained in its inoperative position. When it is desired to place the mirror in its operative position, the rod 11 is withdrawn 100 from the hollow member 10 to support the mirror at any desired height, and it is held in its adjusted position by means of the thumb-screw 12. It is apparent that the upward move- 105

ment of the rod 11 will expand the spring 16 and that by withdrawing the thumb-screw 12 from engagement with the rod 11 the spring is free to return to its normal condition, whereby the mirror will be withdrawn into the position disclosed in dotted lines in Fig. 1. 110 It is apparent that the upward movement of the rod 11 is limited by the degree of expan-

sion of the spring 16, and if such movement is not sufficient to place the mirror at a proper elevation the hollow member 10 may also be adjusted, as is apparent.

5 It is apparent from the above description, taken in connection with the accompanying drawings, that the mirror 15 may be adjusted vertically or horizontally, that it is normally returned to its inoperative position and retained in such position, and that the device is easy of application, cheap to manufacture, durable, and efficient.

Having thus fully described the invention, what is claimed as new is—

15 1. In a mirror-support, a bracket comprising a base-plate carrying a sleeve, a hollow member having its lower end closed and adjustably mounted within said sleeve, a supporting-rod adjustably mounted within said 20 hollow member, a hook member carried by the closed end of said hollow member, a spring

having one of its ends secured to the rod and its other end secured to said hook, and a mirror adjustably carried by said rod.

2. In a mirror-support, a bracket provided with a sleeve, a hollow member adjustably mounted in said sleeve and having its lower end closed, a hook carried by said closed end, a supporting-rod adjustably mounted within said hollow member, a spring having connection with said rod and hook, said rod being provided with a ball, a mirror-frame, and a socket carried by said mirror-frame and adapted to receive said ball to adjustably mount the mirror-frame upon the rod.

In testimony whereof I affix my signature in presence of two witnesses.

GEORGE C. HOHEIN.
